E P Pennington Rochester New York
Letters Patent No 398 dated July 15th 1857

— —

Res. 398

497

The schedule referred to in these Letters Patent and making part of the same -

To all whom it may concern.

Be it known that I Elijah P. Penman of the city of Rochester and county of Monroe and State of New York have invented and invented a new and original design for boxes and I do hereby declare that the following is a full and exact description of the same referred being had to the specimen and accompanying drawings figure 1. Figure 3 is a section showing the end view of figure 1. Figure 2 is N represents the curved work on the V joint

What I claim as my invention and desire to secure by Letters Patent is the ornamental design or production represented by figures 1 and 3 to be used with the carving represented by letter N.
